COVERING TOOL

William H. Nutt, Beverly, Mass., assignor to
United Shoe Machinery Corporation, Paterson,
N. J., a corporation of New Jersey

Original application May 15, 1931, Serial No.
537,635. Divided and this application August
9, 1934, Serial No. 739,157

4 Claims. (Cl. 12—103)

This invention relates to the manufacture of shoes and is illustrated with reference to tools for applying covers to heels.

In an application for United States Letters Patent Serial No. 537,635, filed May 15, 1931, of which the present application is a division, there is described a heel the central portion of the breast of which is provided with three parallel slots located adjacent to each other and extending heightwise of the heel. In covering the heel the forward projecting portions of the side cover are inturned upon the lateral portions of the breast of the heel, the margins of such portions being tucked into the outer two slots, respectively. A separate panel strip is laid upon the portion of the heel breast included between the two outer slots and has its lateral margins tucked into the outer slots alongside the tucked in margins of the side cover. Thin ribs are formed between the central slot and the two outer slots, the ribs being readily flexed as the cover margins are tucked into the slots thereby to expand the slots to expedite the covering operation. After the side cover and the panel strip have been applied to the heel a filler piece is slid in the center slot to insure that the margins of the cover and the strip are securely held within the outer slots.

In order quickly and effectively to tuck the margins of the side cover and the panel strip into the outer slots and to lay the side cover and the panel strip smoothly against portions of the heel breast surrounding the slots, there is provided a pair of tools each of which comprises a pair of spaced tucking blades constructed and arranged simultaneously to wipe the margins of a cover into spaced slots formed in a face of a heel, and means positioned adjacent to the respective blades for applying the cover to portions of the face located adjacent to the respective slots.

In the illustrated construction the tools are rotatable and the tucking blades are of disk-like shape. The tucking blades of one of the tools are tapered toward their marginal edges in order to flex walls or ribs formed between the outer slots and the central slot, thereby to facilitate entry of the blades into the respective outer slots for tucking the cover margins into the slots. The means for pressing and smoothing the margins of the side cover against the breast of the heel includes rolls which are positioned along the outside faces of the blades. The tool for tucking the panel strip into the outside slots is provided

with a roll which is located between the inner faces of the tucking blades.

These and other features of the invention, including certain details of construction, will be described as embodied in an illustrated machine and pointed out in the appended claims.

In the drawing,

Fig. 1 is a cross sectional view of a Cuban heel the breast of which is provided with a triple slot, illustrating the heel in the process of being covered;

Fig. 2 is a cross sectional view of the heel shown in Fig. 1 illustrating the method of tucking the lateral margins of a side cover of the heel into outer slots;

Fig. 3 is a view similar to Fig. 2 but illustrating a further step in the process of covering the heel;

Fig. 4 is a perspective view of a heel in the process of being covered, illustrating the application of a narrow panel strip for covering portions of the heel breast included between the outer slots formed in the breast of the heel;

Fig. 5 is a longitudinal view of the heel in the process of being covered;

Fig. 6 is a perspective view illustrating the trimming of the panel strip to the proper length;

Fig. 7 is a perspective view of a completely covered heel;

Fig. 8 is a cross sectional view of the heel shown in Fig. 7; and

Figs. 9 and 10 respectively are perspective and cross sectional views of a covered Cuban heel illustrating a modified type of construction.

In covering Cuban heels 20 it is sometimes the practice to form outer and center slots 22 and 24, respectively, in the breast 26 (Fig. 1) of the heel, which slots are arranged in parallel relation and extend heightwise of the heel. In applying to the heel 20 a cover 28 which is laid upon the rear and side faces of the heel by the use of cement or other adhesive and is commonly referred to as a side cover, the forwardly projecting portions 30 of the side cover are inturned upon the breast 26 of the heel. The margins of the forwardly projecting portions 30 of the side cover 28 which have been laid upon the heel breast 26 are next trimmed simultaneously to the proper width by moving a hand knife 32 (Fig. 1) guided along the center slot 24 against overlapping forwardly projecting portions 30 of the side cover, and the respective margins of the projecting portions 30 are then tucked into the outer slots 22. In order to cover the portion of the breast 26 of the heel included between the outer slots 22 a panel strip 34 is laid

upon such portion, the lateral margins of which strip are tucked into the slots 22 alongside the tucked-in margins of the side cover 28. It will be understood that the heel and the inside face of the side cover 28 are usually coated with rubber cement prior to the heel-covering operation.

By providing the center slot 24 the tucking of the margins of the forwardly projecting portions 30 of the side cover and the panel strip 34 into the outer slots 22, respectively, is facilitated since ribs or walls 36 (Fig. 3) which are included between the outer slots 22 and the inner slot 24 are temporarily bent under pressure of a tucking tool 38, the construction of which will later be described, thereby to widen the slot 22 and to permit entry of the margins of the cover and the tool. The ribs 36 spring back into their normal positions illustrated in Fig. 8 after the tucking tool has been removed, and effectively clamp the tucked-in margins. In order to fill up the center slot 24 after the heel has been covered and to insure that the tucked-in margins are positively clamped within the outer slots 22, a filler piece 40 (Figs. 5 and 8) is inserted in the center slot 24. The panel strip 34 may be of a different color than the side cover 28 and this gives the heel an attractive appearance.

Figs. 9 and 10 disclose a slightly modified heel 42 provided with a panel strip 44 extending over a substantial width of the breast of the heel. The wide panel strip 44 has its lateral margins tucked into outer slots 46 alongside the tucked-in margins of the side cover. In order to expand the outer slots 46 a pair of inner slots 48 are formed to provide ribs or walls 50 which may be flexed during the tucking operation to increase the width of the slot into which the margins are inserted. A filler piece 52 similar to the filler piece 40 may be inserted within each of the inner slots 48 when the margins of the side cover and the panel strip 44 have been securely tucked into the outer slots 46.

In order quickly and effectively to tuck the margins of the side cover 28 into the outer slots 22 a rotary tool 54 (Fig. 2) is provided. The tool 54 may be rotated under pressure and translatory movement of the heel or may be positively rotated at a slow rate of speed. The tool 54 comprises a pair of spaced disk-like tucking blades 56 and a pair of rolls 58 positioned adjacent to the outside faces of the blades 56 and constructed and arranged to lay the margins of the side cover against portions of the breast which are located adjacent to the slots 22, respectively.

The widthwise curvature of the work-engaging faces of the rolls 58 is substantially complementary to the transverse curvature of the breast of the heel.

The margins of the panel strip 34 may be tucked into the slots 22 alongside the tucked-in margins of the side cover by the above-mentioned rotary tool 38 which comprises a pair of spaced disk-like tucking blades 60 and a strip-applying roll 62 interposed between the blades and constructed and arranged to force the panel strip 34

against the portion of the breast of the heel included between the outer slots 22 as the margins of the strip 34 are tucked into the slots. The rolls 58 of the tool 54 and the roll 62 of the tool 38 are preferably made of rubber or like material.

In order to facilitate the tucking of the margins of the panel strip 34 into the outer slots 22, respectively, the portions of the blade 60 which project beyond the roll 62 taper toward their respective outer edges and readily force the ribs 36 toward each other as they enter the slots 22. After the tool 38 has been removed from the slots 22 the ribs 36 spring back to their normal positions illustrated in Fig. 8. The panel strip 34 may be supplied in long lengths mounted upon a shaft 64 (Fig. 4), a length necessary to cover a portion of the heel breast included between the slots 22 being laid upon the heel and the heel then being forced against and moved past the tool 38 to tuck the margins of the strip into the respective slots. The panel strip 34 is then trimmed to the proper length by a pair of scissors 66, as illustrated in Fig. 6.

In covering the heel 42 illustrated in Figs. 9 and 10 the tucking blades and the rolls of the tools 38, 54 are constructed and arranged in accordance with the position of the heel-cover receiving slots 22.

Having described the invention, what I claim as new and desire to secure by Letters Patent of the United States is:

1. A tool for applying covers to heels comprising means for progressively laying a strip of covering material upon a heel surface between parallel slots in said surface, and means for progressively tucking the lateral margins of the strip into such slots as the strip is being laid.

2. A tool for use in applying covers to heels comprising a roll for laying a strip of covering material upon a heel surface between parallel slots therein, and two disks arranged one at each side of the roll for simultaneously tucking the lateral margins of the strip into said slots as the strip is being laid.

3. A rotary tool for use in applying heel covers comprising a roll of yielding material for laying a cover strip upon a heel surface between parallel slots therein, and two disk-like members arranged one at each end of the roll for simultaneously tucking the lateral margins of the strip into said slots.

4. A rotatable tool for use in applying covers to heels comprising a roll for laying a strip of covering material upon a portion of a heel surface located between parallel cover-receiving slots between which is included a third slot spaced from the cover-receiving slots respectively by ribs, and two disks arranged at opposite sides of the roll for simultaneously tucking the lateral margins of the strip into said cover-receiving slots as the strip is being laid, opposing work-engaging faces of the disks being in converging relation to bend the ribs toward each other as the disks enter the cover-receiving slots.

WILLIAM H. NUTT.
